UNITED STATES PATENT OFFICE

104,169

DESIGN FOR A GLASS PLATE OR SIMILAR ARTICLE

Robert A. May, Washington, Pa., assignor to Duncan & Miller Glass Company, Washington, Pa., a corporation of Pennsylvania

Application October 10, 1936, Serial No. 65,248

Term of patent 3½ years

To all whom it may concern:

Be it known that I, Robert A. May, a citizen of the United States, residing at Washington, Pennsylvania, have invented a new, original, and ornamental Design for a Glass Plate or Similar Article, of which the following is a specification, reference being had to the accompanying drawing forming part thereof.

In the drawing, Figure 1 is a plan view of a glass plate embodying my new design, and Figure

2 is a central vertical cross-sectional view of the plate shown in Figure 1.

The dominant feature of the design is the ornamentation applied to the plate. The design is applicable to articles other than plates but which are of similar character.

I claim:

The ornamental design for a glass plate or similar article substantially as shown and described.

ROBERT A. MAY.
